GEORGE A. BRYAN.
By Atty. N. D. Bois.

UNITED STATES PATENT OFFICE.

GEORGE A. BRYAN, OF SPRINGFIELD, ILLINOIS.

WROUGHT-METAL SOCKET FOR LEGS OR STANDARDS OR THE LIKE.

Application filed March 5, 1925. Serial No. 13,241.

To all whom it may concern:

Be it known that I, GEORGE A. BRYAN, a citizen of the United States, residing at Springfield, in the county of Sangamon and 5 State of Illinois, have invented a new and useful Wrought-Metal Socket for Legs or Standards or the like, of which the following is a specification.

The invention relates to sockets such as 10 are used on structures such as trestles, cars, trucks, etc., to connect legs or standards, or the like, with the several structures.

The purposes of the invention are: to provide a socket, preferably of wrought metal, 15 combination lightness and rigidity and capable of quick and easy placing on the structure on which it is used, to admit of inclining the legs or standards laterally outward relative to the structure, and also 20 inclining them outwardly in the direction of the length of the structure; to provide a socket of such form that blanks to form a number of sockets may be punched, and cut in succession from a single metal bar or 25 plate of predetermined width and indefinite length, with very small waste of material, thereby minimizing the cost of construction; and to provide improved structural details as will hereinafter appear.

30 I attain these objects by the means illustrated in the accompanying drawing in which: Figure 1 is a side elevation of a typical structure, in the present instance a carpenter's trestle, equipped with metal sockets embodying my invention: Fig. 2 is 35 an enlarged view of one detached socket embodying invention, viewed from below and looking upward into the socket.

Fig. 3 is vertical section through the same 40 socket, taken on the line 3-3 of Fig. 2;

Fig. 4 is a vertical section through the same socket on the line 4-4 of Fig. 2;

Fig. 5 is a vertical section taken on the line 5-5 of Fig. 1;

45 Fig. 6 is a diagram showing a top view of a metal plate or bar from which two blanks, each suitable for forming a socket, have been cut; and

Fig. 7 is a vertical section through one 50 blank taken on the line 7-7 of Fig. 6.

Similar numerals refer to similar parts throughout all the views.

The sockets will preferably be made from a flat metal plate or bar A of any convenient 55 length and of width corresponding to the length of the sockets which are to be made,

and of suitable thickness, varying according to the required rigidity and strength of the sockets. I have found by experiment that a bar of No. 12 gauge is sufficient for sturdy 60 trestles, such as are commonly used by plasterers and bricklayers, and thinner metal may be used for sockets on ordinary carpenters trestles.

In laying out the work transversely 65 oblique lines a-a, indicated in Fig. 6, will be drawn on the bar to divide its entire length into a series of spaces, the extreme length of each space being equal to the extreme length of the socket which is to be 70 made.

The centers of a series of central gauge 75 holes 9, and the centers of a series of bolt holes 10, will all be located in a straight median line extending the full length of the bar, and the bar will then be cut along the line a-a, to divide it into a series of blanks 12. The holes 9 and 10 will preferably be punched simultaneously with the cutting off 80 of the respective blanks. The blanks are all 85 alike. Each blank has a central gauge hole 9, and two bolt holes 10, all in line with each other.

To form a socket the metal of the blank 90 will be bent downward along the dotted lines 13, upward along the dotted lines 14, outward along the dotted line 15, and outward along the dotted line 16. Here it is to be noted that the angle 19 between the line 16 and the edge 17 of the blank is considerably greater 95 than the angle of the line 15 relative to the edge 17 of the blank. The purpose of this angular difference will be described later.

In case the sockets are used on a trestle, 100 it is usual to spread the legs laterally as shown in Fig. 5, and it is often desirable to spread the legs in the direction of the length of the trestle to increase both the length and the breadth of the base of the trestle. The sockets herein shown and described are 105 adapted to spread the legs laterally, and hold them in the relative positions shown in Fig. 5, and are also adapted to spread and hold the legs in the direction of the length of the trestle as shown in Fig. 1. I have described the sockets as used on a trestle to connect its downwardly extending legs with the body; but it is obvious that they may be inverted and used with equal advantage to connect upwardly-extending spreading 110 standards on a car, a truck frame, or a platform or other stationary structure.

Referring to Figs. 2, 3 and 4 it will be seen that the outer wall 20 of the central part, which I call the box, the end walls 21 and 21', the wings 22 and 23, the stop member 18 off set from the wing 22, and the stop member 19 offset from the wing 23; are all formed from a single blank, and the structure is symmetrical except that the stop 19 is longer than the stop 18, and is offset from the edge 25 of the end wall 21', a greater distance than the stop 18 is offset from the edge 24 of the end wall 21.

The sockets placed on the trestle beam 26 are in pairs, right and left; the pair of right hand sockets incline downwardly towards the left to cause the legs held in the respective boxes to incline towards the right, in the direction of the length of the beam; and the pair of left hand sockets to incline downwardly towards the right to cause the legs held in the respective boxes to incline downwardly towards the left, in the direction of the length of the beam.

The boxes are tapered in order that when the tapered parts of the legs are in the boxes and their inclined faces are in contact with the sides of the beam 26, the legs will be inclined downwardly and laterally, right and left as shown in Fig. 5.

From the foregoing it is clear that the disposal of the stops in different planes one above the other adapts them for the described inclination of the sockets relative to the horizontal underside of the beam 26; it is also clear that by reason of extending the bend in the direction of the length of the wing 23, the necessary increased length of the stop is attained without increasing the width of the blank from which the socket is formed. This expedient simplifies the construction, increases the strength of the stop 19, and results in a considerable saving of material.

The bevel of the boxes of the sockets may obviously be varied to suit different structures, without departure from my invention.

The blanks for light sockets may be sheared from thin metal sheets of suitable width, and may be formed by hand on suitable blocks held in a vice. Heavier sockets may be formed by power presses

equipped with shears, punches and suitable dies. Means for forming the sockets are not part of the present invention, and, therefore, are not shown or described.

To attach a pair of sockets on the beam 26 of a trestle, the sockets will be placed one on each side of the beam, and the stops 18 and 19 of each beam will be held firmly against the underside of the beam and centers corresponding to the respective holes 10 will be marked on both sides of the beam; bolt holes will then be bored or drilled at the respective marked centers; bolts 28 will then be inserted in the holes through both sockets and the holes through the beam, and the nuts 29 will be screwed on the bolts to connect the parts securely.

Having fully described my invention, what I claim as new and desire to secure by Letters Patent is:

1. A wrought metal socket-member for legs, or standards or the like, comprising a tapered box having end walls parallel to each other, wings integral with an extending outwardly from the respective end walls, and stops of unequal length integral with the respective wings, and formed by bending one terminal part of each wing at an angle relative to the wing and adapted to hold the socket-member in inclined relation to the structure with which it is connected.

2. A wrought metal socket-member of the class described, formed from a flat blank having two edges parallel to each other and two inclined edges converging towards each other, and bent to form a tapered box having end walls parallel to each other; wings extending outwardly from said respective end walls and stops of unequal length at one terminal of the respective wings and adapted to hold the socket-member in inclined relation to a structure with which it is connected.

In witness whereof I have hereunto signed my name at Springfield, Illinois, this 20th day of February, A. D. 1925.

GEORGE A. BRYAN.
